DESIGN FOR A WALKER UNIT FOR CONVALESCENTS

Grover W. Gilleland, Steamboat Springs, Colo.

Application January 19, 1939, Serial No. 82,442

Term of patent 3½ years

To all whom it may concern:

Be it known that I, Grover W. Gilleland, a citizen of the United States, residing at Steamboat Springs, in the county of Routt and State of Colorado, have invented a new, original, and ornamental Design for a Walker Unit for Convalescents, of which the following is a specification, reference being had to the accompanying drawing, forming a part thereof,

Fig. 1 is a top plan view of a walker unit for convalescents showing my new design.

Fig. 2 is a side elevational view of the same; and

Fig. 3 is a front elevational view of the same.

I claim:

The ornamental design for a walker unit for convalescents, as shown.

GROVER W. GILLELAND.
